UNITED STATES PATENT OFFICE.

WILLIAM HUBBARD, OF ROCHESTER, NEW YORK, ASSIGNOR TO UNITED SHOE MACHINERY CORPORATION, OF PATERSON, NEW JERSEY, A CORPORATION OF NEW JERSEY.

WORK-POSITIONING MEANS.

Application filed April 6, 1918. Serial No. 227,037.

To all whom it may concern:

Be it known that I, WILLIAM HUBBARD, a citizen of the United States, residing at Rochester, in the county of Monroe and 5 State of New York, have invented certain Improvements in Work-Positioning Means, of which the following description in connection with the accompanying drawings, is a specification, like reference characters 10 on the drawings indicating like parts in the several figures.

This invention relates to work positioning means for use in connection with machines for inserting fastenings in shoes.

15 In certain classes of shoes the sole portions thereof are secured in position by fastenings driven through the sole portions and clinched in the innersole. The machine shown in the patent to Goddu No. 490,624, 20 granted January 24, 1893, is one of the machines which has been commonly used in attaching outer soles to shoes. This machine gives entire satisfaction when the workman uses ordinary care in presenting 25 the work against the gage provided for the purpose of holding the shoe in proper alignment with the fastening inserting mechanism. As a matter of actual factory experience, however, it has been found that 30 fastenings are often driven in such a way as to damage the shoe because of carelessness or undue haste on the part of workmen. This is especially true in performing the operation of nailing the heel seat ends of 35 the outersoles of women's McKay shoes in which operation fastenings are frequently driven so near the edge of the sole as to damage the upper, mar the appearance of the shoe by exposing the heads of the fastenings to view in the finished shoe, and interfere with subsequent finishing operations 40 on the shoe. In the event that fastenings are thus incorrectly driven, their removal is necessitated with consequent loss of time 45 and waste of material. Hence it is the object of the present invention to provide improved work positioning means of such a character as to make up for failure or neglect on the part of the workman in properly 50 positioning the shoe, the work positioning means being so constructed and arranged as to operate automatically to hold and guide the shoe into proper engagement with the work gage and thus into proper alignment 55 with the inserting mechanism. In a pre-

ferred form of the invention, the work positioning means is arranged to engage the inside of the counter portion of the shoe upper to guide and hold the shoe against the work gage of the inserting mechanism 60 as the shoe is moved during progressive fastening inserting operations. In a practical embodiment of the invention, the said positioning means is associated with a work supporting horn which has a work supporting 65 surface fixed against lateral movement and is constructed and arranged yieldingly to press the shoe against the work gage.

Other features and objects of the invention will be apparent from a consideration 70 of the following description in connection with the accompanying drawings, in which,—

Fig. 1 is a view in side elevation of a work support with the work positioning means in 75 place thereon, a portion of the inserting mechanism with its work gage being also shown;

Fig. 2 is a view of the same parts from 80 the other side of the machine;

Fig. 3 is a detail view in section showing 85 parts of a shoe in position on the horn and in engagement with the work positioning means; and

Fig. 4 is a plan view from above of the 85 heel portion of a shoe as properly positioned on the horn by the work positioning means.

In the illustrated embodiment of the invention, the inserting mechanism 6 may be of any well-known form but preferably like that shown in the patent to Goddu referred to above. This mechanism comprises, as essential elements, a driver 8 and an awl 10 which operate through the work rest 12 to feed the work, the work being pressed 90 against the work rest by the work supporting horn 14 in the intervals of feeding and during the insertion of fastenings. In order that the shoe parts may be properly positioned in alignment with the awl and driver, the inserting mechanism is provided with a work gage 16, preferably of the type shown in the patent to Casgrain No. 865,329, granted Sept. 3, 1907. Mounted preferably upon the horn 14 is a work positioning member 100 shown in its illustrative embodiment as a spring member 18 secured at its lower end by a fastening 20 so that the lower end of the member contacts with a shoulder 22 formed by a recess in the horn, the upper 110

end of the member 18 being slightly below the plane of the upper surface of the horn, as shown in Fig. 3. The work positioning member 18 is a flexible flat strip of metal having at its upper end, arms which embrace the upper end of the horn, a pin and slot connection 24 between the upper end 26 of the member 18 and the upper end of the horn being provided to limit movement of the upper end 26 away from the horn. Preferably the upper end of the horn is recessed at each side as indicated at 28, so that the slotted arms 30 play in the recesses, thus avoiding projections on the sides of the horn which might prove objectionable by engaging with the lining of the shoe. The horn illustrated in the drawings is of a well-known type like that disclosed in the said patent to Goddu and in an earlier patent to the same inventor No. 265,227, granted Sept. 26, 1882, and mentioned in the specification of the later patent. This horn 14 is arranged to be depressed by a treadle (not shown) in order that the work may be readily introduced and removed from the machine. The construction in the cited patents to Goddu is such that the horn may be rotated so that fastenings may be inserted in all parts of a shoe bottom, as, for instance, in securing an outersole to a shoe. In heel seat nailing the horn is ordinarily secured against rotation and this is so in the illustrative construction in order that the work positioning member 18 may be retained in position to press the shoe against the gage 16. The work itself is shifted laterally during feeding and fastening inserting operations, the horn being fixed against lateral movement. Preferably the work supporting surface of the horn is provided with a clinching cavity 32 located in the line of fastening insertion and operative to insure proper clinching of the fastenings, as each is driven into and through the work by the driver 8.

In nailing the heel seat end of the sole in place, the shoe is introduced over the upper ends of the horn and the work positioning member 18, the resiliency in the spring member 18 being such that the upper end 26 of the member may be pressed into contact with the horn to provide a space between said upper end 26 and the work gage 16 for the introduction of the shoe parts. Normally there is a considerable space between the upper end of the horn and the work gage so that the shoe may be readily placed in position on the horn and freely turned to present different portions thereof for the insertion of fastenings. The member 18 is so arranged as to project into this space and from one standpoint may be said to take up self-adjustingly the proper portion of this space, thereby causing the shoe parts to be definitely positioned between the combined horn and work positioning member on one

side and the work gage on the other side. It will be obvious, therefore, that the work positioning member 18 will constantly press the shoe yieldingly against the work gage 16 and thus ensure that the fastenings will be driven at proper distances from the edge of the sole. This positioning of the fastenings is secured through the co-operation of the work positioning member 18 and the work gage 16, the latter being arranged to engage the counter portion of the shoe upper, this co-operation resulting in inserting a line of fastenings which follows the contour of the counter portion of the upper and, therefore, at a uniform distance from the edge of the sole. The fastenings thus driven are properly positioned, due to the continuous operation of the work positioning member 18. It is to be understood that applicant's invention is not to be limited to the specific embodiment herein shown and described, as various modifications may be made by those skilled in the art without departing from the scope of the invention as set forth in the appended claims.

Having described my invention, what I claim as new and desire to secure by Letters Patent of the United States is:

1. In a fastening inserting machine, a work support having a work supporting surface fixed against lateral movement; means for inserting fastenings into work on the work support, a work gage and work positioning means co-operating with said support and automatically taking up any excess of space between the support and the gage for holding the work in contact with the gage.
2. In a fastening inserting machine, a work support having a work supporting surface fixed against lateral movement, means for inserting fastenings into work on the work support, a work gage, and work positioning means mounted on the work support to project into the space between the latter and the gage and operative to hold the work in contact with the gage.
3. In a fastening inserting machine, a work support having a clinching cavity maintained constantly in the path of fastenings being inserted into the work, means for inserting fastenings into work on the work support and for feeding the work between fastening inserting operations, a work gage and work positioning means constructed and arranged to be movable between the work support and the gage and to hold the work yieldingly in contact with the gage throughout the fastening inserting and feeding operations.
4. In a fastening inserting machine, a shoe supporting horn, mechanism for inserting fastenings in a shoe on the horn and for feeding the work between fastening inserting operations, a work gage, and means

for holding the counter portion of the shoe upper against said gage throughout the fastening inserting and feeding operations.

5. In a fastening inserting machine, a shoe supporting horn having a work supporting surface fixed against lateral movement, mechanism for inserting fastenings in a shoe on the horn, a work gage, and means mounted on the horn adjacent to the upper end thereof for entering the shoe with the horn to engage the inner surface of the shoe upper to hold the shoe against the gage.

6. In a fastening inserting machine, a shoe supporting horn having a shoe supporting surface over which the shoe is moved in the intervals of fastening insertion, mechanism for inserting fastenings progressively in a shoe on the horn, a work gage, and means arranged to engage the inner surface of the shoe upper, when the shoe is supported on the horn, to hold the shoe against the gage.

7. In a fastening inserting machine, a shoe supporting horn, mechanism for inserting fastenings in the shoe on the horn and for feeding the shoe progressively with the fastening inserting operations, a work gage, and means positioned below the work supporting surface of the horn and movable with relation thereto and co-operating with the horn to hold the shoe yieldingly against the gage during the feeding and fastening inserting operations.

8. In a fastening inserting machine, a shoe supporting horn having the supporting surface so mounted as to be fixed against lateral movement, mechanism for inserting fastenings in the shoe on the horn, a work gage, and a member mounted on the horn so that its effective portion is subjacent the work supporting surface of the horn for entering the shoe with the horn to engage the inner surface of the counter portion of the shoe and operative in conjunction with the horn for automatically holding the shoe against the gage.

9. In a fastening inserting machine, a shoe supporting horn so mounted as to be fixed against lateral movement, mechanism for inserting fastenings in the shoe on the horn, a work gage, and a resilient member mounted on the horn in such manner that its upper end is subjacent the work supporting surface of the horn, said member and horn being automatically operative for yieldingly pressing the shoe against the gage to hold the same in proper position with respect to the fastening inserting mechanism.

10. In a fastening inserting machine, a shoe supporting horn having a work supporting surface fixed against lateral movement, mechanism for inserting fastenings in the shoe on the horn, a work gage, and a member movable with respect to the horn for engaging the inner surface of the shoe

upper and operative to hold the shoe against the gage and in proper position beneath the inserting mechanism.

11. In a fastening inserting machine, a shoe supporting horn having a work supporting surface fixed against lateral movement, mechanism for inserting fastenings in the shoe on the horn, a work gage, and movable means for holding the shoe against the gage and in proper position with respect to the fastening inserting mechanism. 70

12. In a fastening inserting machine, a shoe horn having a clinching cavity maintained constantly in line with the fastenings as they are driven into the shoe, mechanism for inserting fastenings in the shoe on the horn and for intermittently moving the shoe in the intervals of fastening insertion, a work gage, and movable means associated with the horn for yieldingly holding the shoe against the gage as the shoe is intermittently turned during the fastening inserting operation. 80

13. In a fastening inserting machine, a shoe supporting horn having a shoe supporting surface over which the shoe is moved in the intervals of fastening insertion, mechanism for inserting fastenings progressively in a shoe on the horn, a rotary work gage, and means arranged to engage the inner surface of the shoe upper, when the shoe is supported on the horn, to hold the shoe continuously against the rotary gage during the feeding and fastening inserting operations. 90

14. In a fastening inserting machine, a movable work support, means for inserting fastenings into work on the work support, a work gage, and means, comprising a member having a work engaging end below the work supporting surface of the work support and a resilient shank portion secured to and movable with the work support, for holding the work in contact with the gage. 105

15. In a fastening inserting machine, means for inserting fastenings into work, a work support having a clinching cavity maintained constantly in line with the inserting means, a work gage, and work positioning means for holding the work in contact with the gage. 115

16. In a fastening inserting machine, means for inserting fastenings progressively in work, a work support constructed and arranged for movement toward and from the inserting means and having a work supporting surface over which the work is moved during the progressive insertion of fastenings, and work positioning means mounted on and movable with the work support and constructed and arranged to accommodate itself to the work to hold the latter in proper fastening receiving position throughout the fastening inserting operations. 120

17. In a fastening inserting machine, means for inserting fastenings, a shoe supporting horn having a fastening clinching cavity at the upper end thereof maintained constantly in line with the inserting means, a work gage, and means mounted on the horn and extending toward the gage to hold the shoe over toward the gage.

18. In a fastening inserting machine, means for inserting fastenings, a shoe sup-

porting horn having a fastening clinching cavity at the upper end thereof maintained constantly in line with the fastening inserting means, a work gage, and a member mounted on the horn and operative to hold the shoe over toward the gage.

In testimony whereof I have signed my name to this specification.

WILLIAM HUBBARD.
